UNITED STATES PATENT OFFICE.

NELS K. NELSON, OF LAKE MILLS, IOWA.

END-GATE FASTENER.

1,306,117.

Specification of Letters Patent. Patented June 10, 1919.

Application filed June 25, 1917. Serial No. 176,864.

To all whom it may concern:

Be it known that I, NELS K. NELSON, a citizen of the United States, residing at Lake Mills, in the county of Winnebago and State of Iowa, have invented certain new and useful Improvements in End-Gate Fasteners, of which the following is a specification.

My invention relates to new and useful 10 improvements in end gate fasteners.

The primary object of the invention is the provision of a device of this character which is carried by the end gate and adapted to engage the sides of the wagon body whereby 15 the end gate may be easily removed or replaced.

A further object is the provision of means 20 for adjusting the fastener to accommodate end gates and wagon bodies of various widths.

Another object is the provision of a device of this character which may be connected to the end gates and wagon bodies now commonly in use.

25 With these and other objects in view, the invention consists in the novel details of construction and arrangement of parts which will be more clearly understood from the following description and drawing, in 30 which—

Figure 1 is a rear end view of the wagon body with the end gate and fastener in position, and

Fig. 2 is a longitudinal section on the line 35 2—2 of Fig. 1 looking in the direction of the arrows.

In the drawings the numeral 1 indicates 40 the bottom of the wagon body and 2 the sides thereof. Vertical strips or cleats 3 are connected to the inner faces of the sides 2 and as is more particularly illustrated in Fig. 2 of the drawings these cleats are 45 spaced apart to receive the end gate 4 therebetween. Vertical strips 5 are secured to the outer side of the end gate 4 and are provided with the longitudinal grooves 6 for the purpose that will be presently described. Grooves 7 are formed in the outer cleats 3 and grooves 8 are formed in the 50 ends of the sides 2 for the purpose that will be presently described. Plates 9 are secured to the outer faces of the sides 2 and are provided on the outer end with a notch adapted to register with the grooves 8 in 55 the sides 2. The end of the plates 9, on

each side of the notch is bent at right angles to form the projections 10.

A rod 11 is received in the grooves 6 of the middle strip 5 and one of the end strips and is held therein by means of plates 60 12 which overlie the rod and grooves. A link 13 is received in the grooves of the opposite end strip 5, said strip being provided with two grooves 6 which are vertically spaced. A plate 14 is secured to the 65 strip and overlies both of the grooves as well as the link. A rod 15 is connected to the link by means of the eye 16 formed on the end of the rod and said rod 15 is provided on the opposite end with an enlarged 70 head 17. This rod 15 will pass through the groove 7 formed in the strip or cleats 3 and the groove 8 formed in the sides 2 and through the notch formed in the plate 9. The enlarged head 17 will be received behind 75 the projection 10 as is more particularly illustrated in the drawings. A rod 18 provided with an eye 19 is connected to the eye 20 formed on the end of the rod 11 and the outer end of the rod 18 is 80 threaded as indicated at 21 to receive a nut 22 which is adapted to be received behind the projection 10 formed on the plate 9. By having the eyes 16 and 19 on the rods 15 and 18 respectively, it will be seen that they are 85 pivotally connected to the link 13 and rod 11 respectively. The rod 18 will pass through the groove 7 formed in the cleat 3, the groove 8 formed in the sides 2 and the notch formed in the plate 9. A lever 23 90 having the perforated ears 24 is pivotally connected to the link 13 by said link passing through the opening in the ears and the lever is provided with an integral projection having an opening 25 adjacent the end 95 thereof to receive the end of the rod 11 which is bent to form an eye 26 whereby the rod 11 is connected to the lever.

Having fully described the detailed construction it is thought that the manner of 100 operating and the advantages will be clearly understood. It will be seen that I have provided an end gate fastener which can readily be connected to the wagon bodies and end gates now commonly in use and 105 which may be adjusted, by operating the nut 22 on the threaded rod 21, to accommodate end gates or wagon bodies of various widths. It will also be noted that the fastener is also carried by the end gate so that all of 110

the parts will be in position for ready attachment to the wagon body. While I have illustrated the fastener on a solid end gate it will be understood that it could as equally well be used on an end gate formed in sections which are hingedly connected together. In the drawings the fastener is illustrated, in full lines, locking the end gate in position and in dotted lines Fig. 2, with the parts released whereby the end gate may be removed. When it is desired to remove the end gate the lever 23 is rocked outwardly thereby sliding the rod 11 and link 13 in opposite directions whereby the enlarged head 17 of the rod 15 and the nut 22 on the rod 18 will be disengaged from behind the projections 10 whereby the rods may be swung on their pivot points and removed from the grooves formed in the cleats and ends of the sides 2. When this has been done the end gate may be raised and removed from between the cleats. It will be noted that by providing the grooves 6 in the vertical strips 5 a guide will be formed for the rod 11 and the link 13 whereby they will easily slide and be held in position. When the end gate is again lowered between the cleats the rods 15 and 18 are swung in position to lie in the grooves 7 and 8 and the notch in the plates 9 and the lever 23 is then forced upwardly whereby the rod 11 and link 13 will be brought

toward one another and the enlarged head 17 on the rod 15 and the nut 22 on the rod 18 will be drawn against the plates 9 and behind the projections 10.

Having fully described my invention what I claim as new and desire to secure by Letters Patent is:

In combination with a wagon body having plates connected thereto, said plates being provided with lateral slots in the ends thereof, an end gate mounted in said body having grooved strips secured thereto, a rod slidably mounted on one side of the end gate, a link slidably mounted on the opposite side, a securing lever provided with spaced inwardly directed ears pivotally secured to the said link at the inner end thereof, said lever being further provided with an integral projection and aperture to receive the inner end of the said rod, fastening rods pivotally connected to the outer ends of the said link and rod adapted to be slidably received within the slots provided in the ends of the plates, and means for holding the fastening rods within the slots when the lever is forced inwardly.

In testimony whereof I affix my signature in presence of two witnesses.

NELS K. NELSON.
